UNITED STATES PATENT OFFICE

101,794

DESIGN FOR A TRAY

Burke Rummller, Los Angeles, Calif.

Application September 16, 1936, Serial No. 64,881

Term of patent 3½ years

To all whom it may concern:

Be it known that I, Burke Rummller, a citizen of the United States, residing at Los Angles, in the county of Los Angeles and State of California, have invented a new, original, and ornamental Design for Trays, of which the following is a specification, reference being had to the accompanying drawing, forming part thereof.

I claim:

The ornamental design for a tray as shown.

BURKE RUMMLER.
